United States Patent Office

Des. 213,231
Patented Jan. 14, 1969

213,231

TYPEWRITER OR THE LIKE

Gerhard Dietrich, Fuerth, Bavaria, and Alfred Mame, Altenberg, Nuremberg, Germany, assignors to Triumph Werke Nuremberg A.G., Nuremberg, Germany

Filed Oct. 16, 1967, Ser. No. 9,014

Claims priority, application Germany June 21, 1967

Term of patent 14 years

U.S. Cl. D64—11
Int. Cl. D18—01

FIG. 1

FIG. 2

FIG. 3

FIG. 4

FIG. 1 is a perspective front view of a typewriter showing our new design;

FIG. 2 is a front view;

FIG. 3 is a side view; and

FIG. 4 is a top view.

The essential features of our design reside in the portions shown in solid lines, conventional keys and other elements being shown in broken lines.

We claim:

The ornamental design for a typewriter or the like, substantially as shown.
